UNITED STATES PATENT OFFICE.

JOHN R. GAMMETER, OF AKRON, OHIO. ASSIGNOR TO THE B. F. GOODRICH COMPANY, OF NEW YORK, N. Y., A CORPORATION OF NEW YORK.

SOLE AND HEEL CONSTRUCTION.

Application filed March 27, 1922. Serial No. 547,028.

To all whom it may concern:

Be it known that I, JOHN R. GAMMETER, a citizen of the United States, residing at Akron, in the county of Summit and State 5 of Ohio, have invented a certain new and useful Sole and Heel Construction, of which the following is a specification.

This invention relates to the bottom construction of footwear, and its object is to 10 provide a sole or heel, or a combined sole and heel, of moldable material such as rubber and fiber stock having improved characteristics including increased stiffness in certain portions, enabling the sole or heel to be 15 firmly attached to the shoe body by ordinary fastening means and decreasing its liability to slip, decreasing the liability of the heel to catch on rugs, carpets, etc., enabling the shoe better to retain its shape, and affording 20 an improved arch support.

Of the accompanying drawings, Fig. 1 is a vertical section, partly in elevation, showing the lower portion of a shoe provided with a combined sole and heel constructed 25 according to my invention.

Fig. 2 is a reverse plan view, partly broken away.

Fig. 3 is a reverse plan view of a heel embodying my invention. 30 Fig. 4 is a section on the line 4—4 of Fig. 3.

Referring at first to Figs. 1 and 2, 10 is the sole portion and 11 the heel portion of a combined sole and heel or a shoe-bottom, 35 and 12 is the upper body of the shoe, including an upper 13, an insole 14, a welt 15, and a counter-stiffener 16. The shoe-bottom 10, 11 has an attaching and stiffening portion 17, preferably composed of rubber mixed 40 with cotton fiber and vulcanized to a considerable degree of stiffness corresponding to "semi-hard" rubber. 18 is a metal plate embedded in said portion at the shank and constituting a shank stiffener or reinforcement. 45 The stiff material 17 extends down to the tread surface of the sole around the edges thereof, in order to improve the grip of the sole upon the ground as compared with a soft rubber or composition sole, and a cushioning portion 19 of soft, vulcanized rubber and fiber composition is provided as the main tread of the sole. The stiff material 17 is also extended to the tread of the heel 50 11 at the front or breast portion 20 thereof, and the rear tread portion 21 of said heel

is formed of soft, vulcanized rubber and fiber composition. This rear portion forms a good wearing surface, while the stiffened breast part 20 aids in preventing slipping on wet pavements, etc., furnishes an improved 60 arch support and has less tendency to catch and snub under on rugs, carpets and other obstructions, than the ordinary rubber heel. The heel part 11 is secured to the inner sole 14 by nails 22, and a suitable cement may 65 be interposed between the body and the shoe bottom.

In the manufacture of my improved shoe bottom, it is preferred to employ a mold having two covers, one of which is provided with projections adapted to form the recesses in the stiff composition in which the soft portions 19 and 21 are to be placed, and the other cover being substantially flat to form the ultimate tread surface. The 70 highly sulfurized stock for the stiffened portion 17 is first placed in the mold, with the shank-stiffener 18 embedded therein, and the mold cover having the projections thereon is used while the material is given a 75 partial cure in a heated press. The first cover is then removed, the softer stock for the portions 19 and 21 is laid in place, and the flat cover is applied to the mold, after which the vulcanization is completed in the 80 press, the resulting product having its parts 85 firmly vulcanized together.

The combined sole and heel structure is then ready for attachment to the shoe in any suitable manner as by cementing, followed by the use of heel-nails 22 and a suitable form of sole attachment such as stitching 23 through the sole 10 and the welt 15. To receive the stitches a channel 90 may be cut in the sole by separating the soft tread portion 19 from the stiff portion 17 at their line of junction, and then cementing the soft flap back in place or leaving an open cut with the stitches therein.

In Figs. 3 and 4 is shown a heel or lift 100 11^a of my improved construction, preferably made of rubber and fiber composition and having a stiffened or semi-hard attaching portion 17^a extended to the tread at the front or breast 20^a and a soft, rear tread portion 21^a vulcanized to the attaching portion. To increase the adhesion between the portions 17^a and 21^a, the former may be formed with under-cut holes into which 105 studs 21^b of the softer material are molded. 110

This heel lift is preferably attached by nails driven through from the tread side in the usual manner and the stiffened portion 17^a dispenses with the necessity of using washers to retain the nail-heads. 24 are the nail holes through the hard and soft portions, which are contracted in the soft portion 21^a, and 25 are the nail-holes in the stiffened portion alone, which have enlarged mouths 10 for the removal of the mold-pins, and these mouths may be filled by cementing soft-rubber or composition plugs 26 therein, said plugs being centrally perforated at 27 to vent the air when they are forced into place; 15 or these plugs may be made of any other suitable material and may be secured in place with a driving fit, by cementing or otherwise. Besides acting to fill the nail holes and keep out dirt, they also, if made 20 to project as shown, tend to overcome slipping.

It will be understood that the tread surface or surfaces may have any suitable formation other than the flat formation shown, 25 and the details of construction may be variously modified without departing from my invention.

I claim:

1. A ground-contacting member for foot-wear having a tread part of soft-rubber

composition and an attaching part of stiff-rubber composition overlying substantially the whole top area of said tread part, integrally united therewith by vulcanization, and extending to the tread surface at the 35 edge of said member.

2. An integral combined shoe-sole and heel having an attaching portion of stiff-rubber composition extended to the tread surface in both the sole and heel, and sole 40 and heel tread-portions of soft-rubber composition.

3. An integrally combined shoe-sole and heel having a heel-tread portion and a sole-tread portion of soft-rubber composition 45 and an attaching portion of stiff-rubber composition vulcanized thereto and extended to the tread surface around the toe and side edges of the sole and across the breast of the heel.

4. A shoe-heel comprising an attaching portion of stiff-rubber composition extended to the tread surface at the breast edge, and a rear tread portion of soft-rubber composition vulcanized thereto, said attaching portion overlying substantially the whole top area of said soft-rubber composition.

In witness whereof I have hereunto set my hand this 25th day of March, 1922.

JOHN R. GAMMETER.
